(57) **CLAIM**

The ornamental design for a rear bumper for an automobile, as shown and described.

DESCRIPTION

FIG. 1 is a front view of a rear bumper for an automobile showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and left side perspective view thereof; and,

FIG. 8 is a top, rear and right side perspective view thereof. The portion of the rear bumper shown in a de-emphasized faded out half-tone manner is for illustrative and environmental purposes that form no part of the claimed design.
